UNITED STATES PATENT OFFICE.

ALBERT VANAUKEN, OF LUDLOWVILLE, NEW YORK.

IMPROVEMENT IN BRIDLE-BITS.

Specification forming part of Letters Patent No. 120,913, dated November 14, 1871.

To all whom it may concern:

Be it known that I, ALBERT VANAUKEN, of Ludlowville, in the county of Tompkins and State of New York, have invented a new and useful Improvement in Bridle-Bit; and I do hereby declare that the following is a full, clear, and exact description thereof, which will enable others skilled in the art to make and use the same, reference being had to the accompanying drawing forming a part of this specification, in which the figure is a side view of my improved bit, part being broken away to show the construction.

My invention relates to hollow bridle-bits, perforated to allow a melted substance to exude therethrough; and consists in the improved construction hereinafter described and subsequently pointed out in the claim.

A is the mouth-piece of the bit. B and C are the rings into which the headstall-straps and the reins are buckled. The mouth-piece A is made hollow to receive the medicine, and has a number of small perforations, a', formed through its

side through which the dissolved medicine or the vapor of the medicine may escape into the horse's mouth. The rings B C are pivoted to plugs b' c', one of which, as b', may be permanently attached to the end of the mouth-piece A. The other plug c' has a screw-thread cut upon it to screw into a screw-thread cut in the inner surface of the end of the mouth-piece A to enable the said plug c' to be conveniently detached when required for the insertion of the medicine. If desired both the plugs b' c' may be screwed into the ends of the mouth-piece A.

Having thus described my invention, I claim as new and desire to secure by Letters Patent—

A perforated tubular bridle-bit, having its ends closed by screws formed on or attached to the cheek-pieces, as and for the purpose specified.

ALBERT VANAUKEN.
